(57) **CLAIM**

The ornamental design for a conveyor belt, as shown and described.

DESCRIPTION

FIG. 1 is a top view showing our new design for a conveyor belt,

FIG. 2 is a left side view thereof,

FIG. 3 is a cross-sectional view taken along the line 3-3 on FIG. 4,

FIG. 4 is a front view thereof,

FIG. 5 is an enlarged front view of a rib;

FIG. 6 is an enlarged front view of middle ribs,

FIG. 7 is an enlarged side view of a lower end of a side rib,

FIG. 8 is an enlarged cross-sectional view of middle ribs taken along the line 8-8 on FIG. 6,

FIG. 9 is an enlarged side view of an upper end of a side rib,

FIG. 10 is an enlarged cross-sectional view of a rib taken along the line 10-10 on FIG. 5,

FIG. 11 is a top view showing our new design for a conveyor belt,

FIG. 12 is a left side view thereof,

FIG. 13 is a front view thereof,

FIG. 14 is a cross-sectional view taken along the line 14-14 on FIG. 13,

FIG. 15 is an enlarged front view of a rib,

FIG. 16 is an enlarged side view of a lower end of a side rib,

FIG. 17 is an enlarged cross-sectional view of middle ribs taken along the line 17-17 on FIG. 18,

FIG. 18 is an enlarged front view of middle ribs,

FIG. 19 is an enlarged side view of an upper end of a side rib,

FIG. 20 is an enlarged cross sectional view of a rib taken along the line 20-20 on FIG. 15,

FIG. 21 is a top view showing our new design for a conveyor belt,

FIG. 22 is a left side view thereof,

FIG. 23 is a cross-sectional view taken along the line 23-23 on FIG. 24,

FIG. 24 is a front view thereof,

(Continued)

FIG. 25 is an enlarged front view of a rib,
FIG. 26 is an enlarged front view of middle ribs,
FIG. 27 is an enlarged side view of a lower end of a side rib,
FIG. 28 is an enlarged cross-sectional view of a rib taken
along the line 28-28 on FIG. 25,
FIG. 29 is an enlarged cross-sectional view of middle ribs
taken along the line 29-29 on FIG. 26; and,
FIG. 30 is an enlarged side view of an upper end of a side
rib.

1 Claim, 30 Drawing Sheets**Related U.S. Application Data**

having an international filing date of Feb. 22, 2016,
now Pat. No. Des. 812,335.
